PRINTING MACHINE

Charles H. Sand, Jr., Willoughby, Ohio, assignor
to Addressograph-Multigraph Corporation,
Cleveland, Ohio, a corporation of Delaware

Application October 10, 1940, Serial No. 360,573

1 Claim. (Cl. 101—306)

This invention relates to a portable manually-operable printing or addressing machine and particularly to a comparatively small device adapted to be carried from place to place and manipulated by one hand of the operator to impress characters on a suitable record sheet.

More particularly, the device of this patent in its preferred form comprises a head adapted to carry a removable embossed plate with an inking ribbon extending across it and a platen adapted to force the record material against the ribbon to receive an impression from the plate. The head is provided with a handle, preferably in the form of a pistol-grip, and the platen is operated by a finger lever adjacent the handle, so that the operator can carry the device and effect the impression with one hand.

My invention is illustrated in the drawings hereof, and the preferred embodiment thereof shown is hereinafter more fully explained.

In the drawings, Fig. 1 is a plan of the printing device; Fig. 2 is a side elevation thereof; Fig. 3 is a front view, with the handle partly broken away; Fig. 4 is a plan of an illustrative embossed plate which may be employed in the printing device; Fig. 5 is a horizontal section through the device in a plane indicated by the line 5—5 on Fig. 6; Fig. 6 is a vertical section through the entire device; Fig. 7 is a detail in vertical section in a plane indicated by the line 7—7 on Fig. 6; Fig. 8 is a vertical section in the plane indicated by the line 8—8 on Fig. 6.

The main frame of the printing device is preferably one integral member comprising a head 10, a shank 11 extending rearwardly therefrom and a handle 12 extending downwardly from the shank and formed with a forwardly upwardly extending open groove 13 into which the operating handle may extend. The head carries on its under face the embossed plate, and on its opposite sides ribbon spools from which an inked ribbon extends beneath the plate, as herein-after explained.

The platen carrying frame of this device comprises a hollow arm 20 bifurcated to provide two rearwardly extending spaced wings 21 which extend onto opposite sides of the shank of the main member to which it is pivoted by a transverse pin 30. This platen arm carries special platens as hereinafter described to coact with the ribbon and plate.

The operating lever 40 of the device lies in the front portion of the handle groove 13 and is pivoted by a pin 41 extending into ears 14

5 which project forwardly from the handle member, at opposite sides of the groove. At its upper end the lever 40 is provided with a recess 42 bounded by a lug 43 in front thereof and a lug 44 of less height at the rear. The recess is normally occupied by a roller 50 which lies within the hollow platen member 20 and is journaled on a pin 51 mounted in the downwardly extending side portion of such member. A tension spring 55 is anchored at its upper end to a pin 56 carried by the platen member and at its lower end to the pin 57 carried by the back of the handle member. This spring lies within the groove of the handle member, as shown particularly in Fig. 6, and tends to maintain the roller 50 down in the recess at the upper end of the operating handle 40 and such spring action normally holds the operating handle in the position shown in Fig. 6. The lug 43 in front of the roller 50 prevents rearward movement of the upper end of the handle but the lug 44 is low enough and gradual enough so that it can move beneath the roller. The result is that if the operator, grasping the handle 12, pulls the lever, by his fingers, into the groove 13, the lug 44 rides beneath the roller 50 stretching the spring 55 and forcing the platen carried by the arm 20 into coaction with the ribbon and plate to effect the printing.

Referring now to the plate and the means by which it is carried by the head, a specimen plate is indicated at A in Fig. 4. My machine is adapted for printing either or both of two sets of embossed data on the plate, as for instance, two related addresses as indicated at a and a—1 on Fig. 4. Such plate may conveniently be a tag provided with an opening a—2 by which it may be carried by a cord or hook, for instance.

40 The plate also may have a recess a—3, eccentrically placed at the end, cooperating with a suitable stop on the printing device to insure the plate being inserted right side up and right end foremost.

45 Secured to opposite sides of the head 10 are two strips 60 having inturned flanges 61 directly below the underface of the head 10, which underface is flat in the region between the strips and above the flanges. An embossed plate, such as illustrated in Fig. 4, for instance, may be slid into place from the end of the device above the flanges 61 with the type facing downwardly. A suitable pin 62 carried by the head is adapted to coact with the notch a—3 in the plate and allow it to reach final position, shown in Fig. 1,

only when the plate is inserted that end foremost and with the type on the plate facing downwardly.

The platen member is normally locked in an inactive position by a slideable latch bar 70 which is mounted on the underside of the shank 11 and has a limited movement along such shank, the latch having slots 71 through which pins 72 pass into the shank. A suitable compression spring 74 mounted in a recess in the shank at the rear of the latch tends to force it forward and normally holds a shoulder 75 of the latch in engagement with a plate 25 rigidly secured to the platen arm. This is the position of the parts indicated in Fig. 6, where it will be seen that the latch locks the platen arm against operation.

When a properly positioned plate is inserted to the limit of its inward movement, so that the notch *a*-3 comes about the stop pin 62, the end of the plate abuts the front end of the latch 70 and forces it rearwardly, thus causing the shoulder 75 to clear the plate 25 to release the platen arm, and then the operating lever 40 may be actuated to swing the platen arm upwardly to effect the printing.

The strips 60 preferably extend forwardly of the head 10, as shown in Figs. 1, 2 and 6, to provide guides for the plate. This makes it a simple matter, when the operator holds the device in one hand grasping the handle 12 and with his fingers about the lever 40, for him to use his other hand to place the plate in this guideway and then shove it rearwardly into place beneath the head to release the latch 70. A suitable spring acting on the edge of the inserted plate provides friction sufficient to overcome the force of the light spring 74 so that the fully inserted plate will remain in position. The spring providing this friction may conveniently be made by bending inwardly one of the strips 60, as shown at 60*a* in Fig. 1.

To provide ink for the impression, I mount on the head an inked ribbon 88, the ends of which are wound up on two spools 81. These spools lie in recesses 17 formed in opposite sides of the head 10. The forward ends of the spools have their bores extending over short pins 82, Fig. 1, carried by a removable front plate 84 which is secured by screws to the head 10. The rear end of the spools extend over and are connected to pins 85 slidably and rotatably mounted in web positions 18 of the head on opposite sides of the shank portion 11. These pins have knurled heads 86 by which they may be turned. Surrounding the pins are helical springs 87 compressed between the webs 18 and washers 88 loosely surrounding the pins and stopped by transverse pins 89 extending through the pins 85. The spools have diametric notches at their rear ends adapted to receive these cross pins 89.

The result of the construction described is that the spools are rotatably mounted in the head to carry the ribbon, which passes downwardly from one spool across the plate and upwardly to the other. Either spool may be rotated by its knurled head 86 to bring a fresh portion of the ribbon into coaction with the plate. The springs 87 not only hold the pins 85 in engagement with the spools but hold the forward ends of the spools against the plate 84 and thereby apply sufficient friction to enable the ribbon to be maintained under proper tension.

The spools are normally encased by a removable sheet metal hood 80 which extends length-

wise over the head and is clamped in place by a pin 81 which is mounted in the frame head 10 and at its lower end is surrounded by a compression spring 82 acting on the pin to hold it normally down on the hood. The lower annular portion of the head of the pin enters a circular enlargement of a slot 83 in the hood and the shoulder 81—a above such portion presses downwardly on the hood. When the pin 81 is lifted, its head frees the hood and the latter may be drawn off forwardly to furnish access to the spools, thereby enabling the fresh ribbon to be installed whenever desired.

The hood 80 is provided at its lower edges with inwardly flanged extensions 84 which lie directly beneath the flanges 81 of the plate holding strips and thus serve as a mask defining the printing area. The hood is provided at its forward end with a flat looped member 86 which extends outwardly and then downwardly a short distance in front of the plate 84 and then inwardly into an opening in the plate. This not only prevents any displacement of the hood, which is a comparatively thin sheet metal member, but provides a convenient device to enable it to be drawn off, whenever desired, by the insertion of any suitable blade like a screw driver behind the loop.

I have referred to the plate A of Fig. 4 as carrying two related legends and to the machine as being able to print either or both of them as desired. In effecting such printing I provide two platen members side-by-side mounted on the platen arm 20, either or both of which members may be raised so as to be active for printing. Thus, as shown in Figs. 5 to 8, I provide two bars 100 and 101 pivoted by a transverse pin 102 to the platen arm 20. The bar 100 carries on its upper face a rubber platen block 104 and the bar 101 carries a platen block 105 shown as wider than the block 104. The two arms 100 and 101 rest on a pin 110 mounted in the platen arm 20 and are maintained in engagement with such pin by springs 106 and 107, respectively, which are attached at their upper ends to pins 108 depending from the bars and at their lower ends to a cross pin 109 carried by the platen arm.

The control pin 110 is formed with two flat faces diametrically opposite each other. That is to say a flat face 111, Fig. 7, which is shown as in engagement with the bar 100 and a flat face 112 which is shown as on the under-side of the pin and distant from the bar 101. With the control pin in this position the bar 101 is at a sufficient elevation so that when the platen arm is operated by the lever 40 an impression will be made between the platen 105 and that portion of the embossed plate which is directly above it.

If the control pin 110 were turned 180° then the platen 104 would be raised to active position and the platen 105 released and drawn by its spring 107 to idle position. With that setting the handle 40 would print from the portion of the plate corresponding to the platen 104. If the control pin 110 were turned 90° from the position shown in Fig. 7 the cylindrical portion of the pin would engage both bars 100 and 101 and both platens 104 and 105 would effect an impression.

The control pin 110 has sufficient friction in its mounting to prevent displacement but is readily turned by a knurled head 115 on the pin. A suitable mark on the knurled head and cooperating indicia on the side of the platen arm, as indicated in Fig. 3, may show the user at a glance the setting of the control pin. Thus, 75 with the arrow pointing to the numeral "3" as

shown in Fig. 3, the indication may be that the wide platen only is active, printing three lines of type, for instance, the group *a* in Fig. 4. If however, the arrow pointed to the numeral "2" then only the narrow platen would be active and printing two lines of type, as in the group *a-1*. If the arrow pointed to "5," both platens would be active for printing five lines, which could be the groups *a* and *a-1*.

It will be seen that my printing machine is a comparatively small, simple device, which may be readily carried about and conveniently manipulated by the hand of the operator. The formation of the handle into the form of a pistol grip and the forming of the operating lever to be readily forced into the hollow of that grip by the fingers of the hand engaging the grip provide very convenient means for carrying the device and operating it. The operating parts are compactly arranged within the instrument itself and are carried primarily by the two main members, namely, the head frame and the platen frame. The independent platens are carried in simple manner and easily selected. The plate is readily inserted and can only reach position to release the platen arm when its type face is in the proper position for printing. The ribbon is readily mounted and easily replaced whenever necessary, but is entirely protected in use.

Such a device as herein shown and described has a wide variety of uses. For instance, in store tokens it is very convenient to carry several lines of type. For instance, it might be desired to have a man's name with his office address and his wife's name with the house address for rendering accounts at either place or

for making a proper entry for delivery to the house and the bill sent to the office. In keeping track of payrolls in some operations, it is desirable to have the workmen carry a tag and present it to an attendant of certain stations. In some large hospitals each patient is supplied with a tag and imprint is made therefrom by the nurse on the permanent hospital record from time to time in connection with operations or medicines supplied or other items of which a record is to be kept in association with the particular patient. These uses are cited merely as examples to indicate the large variety of uses to which the device may be put.

Reference is made to my copending application No. 387,158, filed April 7, 1941, for claims on the platen operating mechanism including the means for printing by either of a plurality of individual platens, and to my application No. 387,159, filed April 7, 1941, for claims relating to the normally active latch for the platen, released by the insertion of the printing plate in the proper position.

I claim:

25 In a device of the character described, the combination of a head formed to carry a removable printing plate, a shank leading rearwardly from the head, a handle extending downwardly from the shank and grooved on its front side, a platen arm pivoted to the shank, a lever pivoted to the shank adjacent the top of the handle, a roller on the arm which is engaged by a camming surface at the upper end of the lever, and a spring in the hollow handle attached to the handle and arm for maintaining the roller in engagement with the lever.

CHARLES H. SAND, JR.
